UNITED STATES PATENT OFFICE.

EDWARD L. WATSON, OF WASHINGTON, DISTRICT OF COLUMBIA.

ADJUSTABLE FULCRUM FOR VETERINARY DENTAL FORCEPS.

1,403,581.

Specification of Letters Patent. Patented Jan. 17, 1922.

Application filed June 4, 1921. Serial No. 474,933.

To all whom it may concern:

Be it known that I, EDWARD L. WATSON, a citizen of the United States, and resident of Washington, in the District of Columbia, have invented a new and useful Adjustable Fulcrum for Veterinary Dental Forceps, of which the following is a specification.

The object of my invention is to provide a novel adjustable fulcrum which is formed 10 from a single block of rubber and which may be readily attached to dental forceps to provide a fulcrum element to aid veterinarians in extracting teeth; and to provide a fulcrum for this purpose having a novel beveled 15 face adapted to rest on the beveled crown of the teeth of a horse, whereby to hold the forceps in a level position during the operation of extracting teeth. It is also an important object of my invention to provide a fulcrum 20 which can be readily adjusted to a position close to or farther away from the jaws of the dental forceps, so that if certain teeth are missing the device can be adjusted to rest on teeth farther front in the mouth of the horse, 25 while a back molar is being extracted. I attain these and other objects of my invention by the mechanism illustrated in the accompanying drawing, in which—

Figure 1 is a side elevation, with my device 30 shown in full lines in a position in proximity to the jaws of the forceps, and in dotted lines in a position to which it may be adjusted farther from the jaws of the forceps;

Fig. 2 is a section on line 2—2 of Fig. 1;

Fig. 3 is a section on line 3—3 of Fig. 1; and

Fig. 4 is a perspective view of my device removed from the forceps.

Like numerals designate like parts in each 40 of the several views.

Referring to the accompanying drawings illustrating my invention, the fulcrum 3 is adjustably and removably mounted on and secured to the forceps 1 by suitable, preferably rubber, bands 2 which engage over the extensions 6 and are prevented from becoming disengaged by the ribs or end ridges 7. The fulcrum block 4 has a beveled surface 5 adapted to rest flat on the normally beveled 50 crown of one or more teeth of the horse or other stock, thus keeping the forceps in a level position so that a good grip may be obtained on the tooth to be pulled. By providing a fulcrum of rubber all danger of injury 55 to other teeth is eliminated, and the back teeth may be extracted without danger of

mutilating the mouth of the animal or the causing of unnecessary pain.

I prefer to provide a slightly arched base portion line, preferably having suitable corrugations 8 extending longitudinally of portion 9 whereby the device will be more securely held in its position on the polished surface of the forceps.

I may use simply one of the rubber bands 65 2, which preferably is positioned as near as practicable to the pivot of the forceps, or, as illustrated in Fig. 1, in proximity to the member 4 on the lateral extension 3. When the fulcrum block is adjusted to a position 70 farther from the jaws of the forceps, the rubber band applied to the extension 6 nearest the forceps jaws is moved to a position farther from the block 4 and near the ridge 7, whereby the band will still be retained in a 75 position in proximity to the pivot of the forceps arms.

The position of the fulcrum block 4 on the forceps may be reversed when they are shifted to operate on the other side of the mouth 80 of the animal, so that the beveled face 5 of the fulcrum block will, for example, be inclined downwardly when applied to the upper teeth of the animal, the crown of which slant downwardly and outwardly, while the 85 reverse is true of the lower teeth. The adjustability of the fulcrum block is an important advantage of the device which has not heretofore been utilized in this art.

The device is an accessory which may be 90 successfully applied to any type of veterinary molar forceps.

In operating, the tooth is first started or loosened with the forceps by the veterinarian. The fulcrum block may then be applied or shifted by the operator to a reversed position as it rests on the flat surface of the forceps, so that the high side of the fulcrum block will abut against the elongated portion of the tooth on which it rests and fulcrums. 95 An inward and downward tension on the tooth being extracted is thus obtained which is much desired by the operator, in extracting upper teeth, and a reverse operation effected in extracting the lower teeth. Such 100 operation of the forceps facilitates the extraction of the tooth, which is slightly curved and tends to point inward as the extraction progresses. The reversible feature of the fulcrum block on the forceps thus provides 110 an important improvement and aids materially in the extraction of the tooth.

What I claim is:

1. An adjustable and reversible fulcrum for veterinary dental forceps, consisting of a block of rubber, the block having a beveled face which functions as the fulcrum element, and means for adjustably and reversibly securing the fulcrum element on the flat surface of the veterinary forceps.
2. In an adjustable fulcrum for veterinary dental forceps, the combination of a fulcrum block of resilient material, said block having a beveled face functioning as the fulcrum member, the block having one or more extensions, and means removably attaching the device to the forceps and permitting of adjustment of the fulcrum block longitudinally of the forceps arms.
3. As a new article of manufacture a rubber fulcrum block for use with veterinary dental forceps, said block consisting of a

fulcrum portion having a face beveled to rest flat on the crown of the animal's teeth, and having lateral extensions said extensions having upstanding ribs to provide a securing means about which a suitable attaching band may be applied to fasten the device on dental forceps.

4. As a new article of manufacture a rubber fulcrum block for use with veterinary dental forceps, said block consisting of a fulcrum portion having a face beveled to rest flat on the crown of the animal's teeth, and having lateral extensions, the surface of the base portion of the block and extensions being slightly arched and having said surface suitably corrugated to prevent slipping of the block on the polished surface of the portion of the dental forceps to which it is applied.

EDWARD L. WATSON.
